US00D922377S

(12) **United States Design Patent** (10) Patent No.: **US D922,377 S**
(45) Date of Patent: **** Jun. 15, 2021**

(54) **SMART WATCH**

(71) Applicant: **Fitbit, Inc.**, San Francisco, CA (US)

(72) Inventors: **Irina Igorevna Kozlovskaya**, San Francisco, CA (US); **Benjamin Patrick Robert Jean Riot**, San Francisco, CA (US); **Anthony Gerald Kern**, Pleasant Hill, CA (US); **Derek Jenchia Loh**, San Carlos, CA (US); **Bernhard Wildner**, San Francisco, CA (US); **Junyong Park**, San Francisco, CA (US); **Jeffrey Andrew Fisher**, Mountain View, CA (US); **Patrick James Markan**, San Francisco, CA (US)

(73) Assignee: **Fitbit, Inc.**, San Francisco, CA (US)

(**) Term: **15 Years**

(21) Appl. No.: **29/722,312**

(22) Filed: **Jan. 28, 2020**

Related U.S. Application Data

(62) Division of application No. 29/635,224, filed on Jan. 29, 2018.

CLAIM

The ornamental design for a smart watch, as shown and described.

DESCRIPTION

FIG. 1 is a top, right side isometric view of a first embodiment of our new design for a smart watch.

FIG. 2 is a right side elevation view of FIG. 1.

FIG. 3 is a left side elevation view of FIG. 1.

FIG. 4 front side elevation view of FIG. 1.

FIG. 5 is a back side elevation view of FIG. 1.

FIG. 6 is a top plan view of FIG. 1.

FIG. 7 is a bottom plan view of FIG. 1; and,

FIG. 8 is a bottom, left side isometric view of FIG. 1.

The broken lines shown in the drawings depict portions of the smart watch that form no part of the claimed design.

1 Claim, 6 Drawing Sheets
